COMBINED CAN AND BOTTLE OPENER, SCALER, AND SCREW DRIVER

Joe L. Davis, Jr., Magnolia, Ark.

Application June 4, 1952, Serial No. 20,033

Term of patent 7 years

(Cl. D44—29)

To all whom it may concern:

Be it known that I, Joe L. Davis, Jr., a citizen of the United States, residing at Magnolia, in the county of Columbia and State of Arkansas, have invented a new, original, and ornamental Design for a Combined Can and Bottle Opener, Scaler, and Screwdriver, of which the following is a specification, reference being had to the accompanying drawing, forming a part thereof.

In the drawing:

Figure 1 is a plan view of the combined can and bottle opener, scaler, and screwdriver, showing my new design;

Figure 2 is an edge elevational view of the combined can and bottle opener, scaler, and screwdriver, looking toward the bottom edge thereof as illustrated in Figure 1, and

Figure 3 is a sectional view thereof taken substantially along a plane as indicated by the line 3—3 of Figure 1.

I claim:

The ornamental design for a combined can and bottle opener, scaler, and screwdriver, substantially as shown.

JOE L. DAVIS, JR.
